UNITED STATES PATENT OFFICE.

WILLIAM W. PHELPS, OF LOS ANGELES, CALIFORNIA.

STOPPER REMOVER.

Application filed January 14, 1925. Serial No. 2,265.

This invention relates to stopper removers of the type employed for removing cardboard sealing disks or stoppers from bottles containing milk or other liquids.

3 An object of the invention is to provide an inexpensive device of this character so that it can be sold at a very low price.

Another object is to make provision for 19 clamping the disk stopper in the stopper remover so that there will be no tendency for the stopper to accidentally fall off of the remover after the stopper has been removed from the bottle. This makes it easy to replace the stopper on the bottle with the 15 device.

Another object is to construct the device so that it will be guided while it is penetrating the disk.

Another object is to construct the device 20 so as to prevent, during the act of penetrating the disk, pressing of the disk down into the liquid in the bottle and thereby cause the same to splash or spill.

Another object is to provide a device of 25 this character that can be made entirely of wire or sheet metal.

Other objects and advantages will appear in the subjoined detailed description.

The accompanying drawings illustrate the 30 invention:

Fig. 1 is a perspective view of a stopper remover constructed in accordance with the provisions of this invention.

Fig. 2 is a longitudinal view of the stopper remover in position on the top of a bottle for engaging the disk stopper which is also shown.

Fig. 3 is a longitudinal view of the stopper remover attached to the stopper disk 40 which is shown in place on the top of a bottle.

Fig. 4 is a perspective view of another form of the invention.

Fig. 5 is a fragmental longitudinal section 45 of the device shown in Fig. 4.

Referring first to Figs. 1, 2 and 3, there is provided a penetrating member 4, preferably having a sharpened end as indicated at 5. The sharpened end 5 is preferably bent 50 downward so that, as the device is moved across the top of the bottle, the point will be thrust downwardly and will penetrate the disk cardboard stopper, indicated at *a* in Figs. 2 and 3.

55 The member 4 connects with a handle 6 of somewhat oval shape and there is pro-

vided a circular member or ring 7 beneath the lower portion of the handle 6 connected to said handle. The plane of the handle is at a right angle to the plane of the member 7.

Preferably the circular member 7 rests against the underside of the lower portion of the handle 6, and, in its normal position, the member 4 presses upwardly against the underside of the circular member. Thus the members 4, 7 constitute clamping jaws. The member 4 is made of metal that has more or less spring character to it so that it is yieldingly held toward the member 7.

70 Preferably the members 4, 6 and 7 are of integral construction, being formed from a single piece of wire, preferably galvanized iron wire.

In this instance, the member 4 is slightly 75 curved downward between its ends and connects at one end with one end of the member 6 which is in the form of a loop; and the other end of the member 6 connects with one end of the circular member 7. The opposite end of said circular member is bent into an eye 8 through which the member 6 passes. It will be readily understood, without further illustration, that the members 4, 6 and 7 80 may be connected together in a different manner than just described, by bending the wire differently.

The handle 6 extends beyond the point of the penetrating member 4, as indicated at 10, and is provided adjacent to the circular 90 member 7 with an upwardly bent portion 9 so that, when the device is positioned as in Fig. 2, the handle portion 10 will rest upon one side of the top in order that, when the device is moved further into engagement 95 with the disk *a*, the handle 6 will properly clear the bottle top to permit the member 4 to slide beneath the disk.

To use the invention described above, the fingers of one hand of the operator will be 100 inserted through the handle 6 and the upper portion of the handle will be grasped thereby, and the device will then be moved laterally across the top of the bottle *b* to the position shown in Fig. 2, thus bringing the 105 handle portion 10 against the bottle top and, consequently, limiting downward thrust of the jaws 4, 7. This movement causes the jaw 4 to penetrate the disk *a*, and the operator will move the device still further to the left in Fig. 2 to move the jaw 7 110 into position approximately central of the

disk *a*, as in Fig. 3. In this position of the device, the disk *a* will be firmly clamped between the jaws 4, 7.

To remove the disk, the operator will pry 5 upwardly on the handle so as to contact the handle on the right side of the bottle top in Fig. 3 with said top and swing the left end of the handle rearwardly and upwardly. This loosens the disk first at one side of the 10 bottle neck and the disk will remain attached to the device. After a portion of the contents of the bottle has been poured out, the disk may be returned to position to seal the bottle by bringing the device into position 15 with the disk *a* above the neck of the bottle and then pressing downward, thus causing the member 7 to press uniformly upon the disk to properly seat said disk in the bottle neck. The device may then be withdrawn 20 from the disk by moving it to the right in Fig. 2. Or, if the bottle is emptied, the disk will not be replaced on the bottle and it may be readily slipped from between the jaws 4, 7 by grasping it edgewise between 25 the fingers and thumb and pulling it out of its clamped position.

It is to be particularly noted that the oval loop handle is of materially greater length than the outside diameter of the mouth of 30 the bottle so that said handle will engage and slide upon opposite portions of the rim of the bottle when the point is penetrating the disk stopper in the mouth of the bottle, as in Fig. 2, to limit pressure of the clamping member upon the stopper and thus prevent squirting out of the milk from beneath the stopper as would occur if the stopper were forced farther into the neck of the bottle. Also the lower side of the handle 35 is provided with the upwardly bent portion 10 in advance of the penetrating point and with another upwardly bent portion 11 rearwardly of the penetrating member so that such portions will lie immediately over and 40 slightly spaced from the bottle rim when the 45

penetrating member is fully inserted in the stopper. These bent portions 10, 11 permit the penetrating member to be forced into the stopper and the handle to engage and slide upon opposite portions of the bottle rim, as 50 explained above.

In the form of the invention shown in Figs. 4 and 5, the device is stamped from sheet metal and the parts that function the same as those previously described for Figs. 55 1 to 3 are indicated by the same reference characters, with the addition of the letter affixes "a". The penetrating member 4^a, in this instance, is stamped from the member 7^a that is in the form of a disk and that 60 constitutes the upper clamping jaw. The upper portion of the handle 6^a is downwardly convex transversely of the handle so as to fit the hand of the person using the 65 device.

I claim:

A stopper remover comprising a clamping member of slightly less diameter than the inside diameter of the mouth of a standard milk bottle, a pointed penetrating member 70 connected at one end with the clamping member and normally lying on one side of the plane of the clamping member, and an oval loop handle on the other side of said plane at a right angle to said plane and of 75 materially greater length than the outside diameter of the mouth of said bottle to engage and slide upon opposite portions of the rim of the bottle when the point is penetrating a disk stopper in the mouth of the 80 bottle to limit pressure of the clamping member upon the stopper, the lower side of the handle having upwardly bent portions that lie immediately over and slightly spaced 85 from the bottle rim when the penetrating member is fully inserted in the stopper.

Signed at Los Angeles, California, this 8 day of January, 1925.

WILLIAM W. PHELPS.
